UNITED STATES PATENT OFFICE.

HERMAN C. MAISE, OF DETROIT, MICHIGAN, ASSIGNOR TO BRIGGS MANUFACTURING COMPANY, OF DETROIT, MICHIGAN, A CORPORATION OF MICHIGAN.

FASTENER.

Application filed August 27, 1923. Serial No. 659,669.

To all whom it may concern:

Be it known that I, HERMAN C. MAISE, a citizen of the United States of America, residing at Detroit, in the county of Wayne 5 and State of Michigan, have invented certain new and useful Improvements in Fasteners, of which the following is a specification, reference being had therein to the accompanying drawings.

10 This invention relates to fasteners and refers more particularly to those designed for attaching trimming material to the frame-work of a vehicle body.

15 An object of the invention is to provide strong and durable fasteners which are preferably secured to a backing for the trimming material and which are adapted to be attached directly to the frame-work of the vehicle.

20 Another object is to provide a backing which is preferably light and yieldable to facilitate quick attachment of the trimming material to or removal from the frame-work and which is sufficiently rigid to reinforce the trimming material whereby the 25 number of fasteners required is reduced to a minimum.

Another object is to provide a backing 30 that is preferably provided with means for holding the trimming material to the frame-work and that preferably forms a definite line for the outside edges of the trimming.

Another object is to provide a fastener 35 which is simple in construction and which can be manufactured at a comparatively low cost.

With the above and other objects in view the invention consists of certain novel features of construction, combination and arrangement of parts as will be more fully described and particularly pointed out in the appended claims.

In the accompanying drawing:—

Figure 1 is a fragmentary sectional view 45 through the fastener embodying my invention and showing the same attached to the frame-work of a vehicle body;

Figure 2 is a sectional view taken on line 2—2 of Figure 1;

50 Figure 3 is a fragmentary perspective view of a slightly modified form of construction;

Figure 4 is a sectional view taken on line 4—4 of Figure 3;

Figure 5 is a cross-sectional view of the 55 construction illustrated in Figures 3 and 4, showing the trimming material applied thereto and showing the same attached to the frame-work of a vehicle body.

Referring now to the drawing in which 60 like characters of reference designate corresponding parts throughout the several views, the numeral 1 designates the trimming material that is adapted to be attached to the sheet metal frame-work 2 of a vehicle 65 body. This trimming material is preferably provided with a backing or stiffening member 3 of some suitable material such as cardboard or Bristol board to which the fasteners 4 are secured. The backing may 70 be of any shape or size desired and any form of fastener may be employed to secure the same to the frame-work. As shown, I preferably use standard glove fasteners, each 75 preferably comprising a hollow knob 5 upon a base 6 engaging one side of the backing and a complementary member having a base 7 engaging the opposite side of the backing and provided with a knob 8 that detachably fits within the knob 5. The base 7 of the 80 complementary member of each fastener is preferably concealed by the trimming material which is preferably secured to the inner face of the backing by some suitable means and which is preferably folded 85 around the edges of the backing and is secured to the reverse side thereof as shown at 9. To provide straight edges for the folds I preferably provide suitable metal strips 20 that are secured to the upper face 90 of the backing 3 at the edges thereof and are provided at their outer edges with longitudinally extending flanges 21 that cover the edges of the backing. As shown in Figure 1 of the drawing, these flanges 21 preferably project beyond the outer face of the 95 backing so that they will hold the trimming material to the framework as well as form straight lines for the outside edges of the trimming material.

In view of the fact the backing 3 reinforces the trimming material, only a few fasteners are required to secure the trimming to the frame-work. The fasteners secured to the 100

backing are preferably attached directly to the frame-work and for this purpose the said frame-work is preferably provided with suitable openings 10 through which the 5 knobs 5 of the fasteners are adapted to be pressed. Thus, relatively large sections of the trimming may be quickly and easily attached to or removed from the vehicle body frame-work.

10 In Figures 3 to 5 inclusive, I have shown a slightly modified construction in which the backing 11 is preferably a channel shaped strip of light gage spring metal. This form of backing is preferably used when it is desired 15 to attach the trimming material to posts or narrow portions of the frame-work and in order to quickly and easily attach the trimming material, I preferably provide fasteners 12 that are preferably similar in construction to the fasteners 4 and that are 20 preferably secured to the backing 11 in a manner similar to the fasteners 4. The trimming material 13 preferably conceals the bases 14 of the fasteners 12 and is preferably 25 folded inwardly around the flanges 15. Thus, when the knobs 16 of the fasteners 12 are pressed through the opening 17 in the frame-work, the flanges 15 will hold the trimming material to the frame-work and 30 will form definite lines for the outside edges of the trimming. The flanges also strengthen and stiffen the light gage metal backing, but at the same time permit it to yield or bend slightly so as to facilitate quick and 35 easy attachment to the frame-work. Inasmuch as the backing 11 is formed of spring metal, it will be readily apparent that the base of the channel will bend slightly when the fasteners 12 are engaged with the frame-work of the vehicle body, consequently the flanges 15 will clamp the trimming material firmly against the framework 2.

While it is believed that from the foregoing description the nature and advantages of the invention will be readily apparent, I desire to have it understood that I do not limit myself to what is herein shown and described and that such changes may be resorted to when desired as fall within the 50 scope of what is claimed.

What I claim as my invention is:—

1. The combination with the frame-work of a vehicle body and trimming material adapted to be attached thereto, of a yieldable 55 metal backing for the material having a flange for holding the same to the frame-work, and a fastener secured to the backing and adapted to be attached to the frame-work.
2. The combination with the frame-work of a vehicle body and trimming material adapted to be attached thereto, of a channel-shaped spring metal backing for said material, and means for attaching said channel-shaped backing to the frame-work whereby 60

the flanges of the channel will hold the material to the frame-work.

3. The combination with the frame-work of a vehicle body and trimming material adapted to be attached thereto, of a spring metal backing for said material having means at the edges for holding the material to the frame-work, and a fastener secured to said backing and having a portion adapted to be attached directly to said frame-work. 75

4. The combination with the frame-work of a vehicle body, of a channel-shaped spring metal strip, trimming material engaging one side of said channel-shaped strip and folded over the flanges of the channel, and means for attaching said channel-shaped strip to the frame-work whereby the flanges of the channel will hold the material to the frame-work. 80

5. The combination with the framework of a vehicle body, of a stiffening member having a yieldable flat metal base, a flange at one edge of the base, trimming material secured to one face of the base and extending around said flange and secured to the opposite face of said base, and means for securing said stiffening member to the framework of the vehicle body whereby said flange will hold said trimming material against the 90 said framework. 95

6. The combination with a sheet metal frame member, of a separate sheet metal backing member having a flange at one edge, trimming material extending over one face 100 of the backing member and folded around said flange, and means securing said backing member to the frame member whereby the flange of the backing member will hold the folded portion of the trimming material 105 against the frame member.

7. The combination with a sheet metal frame member, of a separate sheet metal backing member having a flange at one edge, trimming material extending over one face 110 of the backing member and folded around said flange, and an element engageable directly with the frame member for detachably securing the backing member to the frame member whereby the flange of the backing member will hold the folded portion of the trimming material against the frame member. 115

8. The combination with a frame member, of a vehicle body, of a relatively thin backing member of yieldable material having a flange projecting therefrom, trimming material extending over one face of the backing member and folded around the flange, and means securing the backing member to the 120 frame member whereby the folded portion of the trimming material will be held against the frame member. 125

9. An article of manufacture comprising a sheet of flexible material having a flange 130

at one edge, trimming material extending over one face of the sheet and folded around the flange, and a fastener projecting from another face of the sheet.

5 10. An article of manufacture comprising a backing sheet of flexible material having substantially parallel flanges, trimming ma-

terial extending over one face of the backing sheet and folded around said flanges, and a fastener projecting from the backing sheet between said flanges. 10

In testimony whereof I affix my signature.

HERMAN C. MAISE.
